GARMENT HANGER

William P. Crockett, Jr., Chicago, Ill., assignor
to Mackie-Lovejoy Manufacturing Co., Chi-
cago, Ill., a corporation of Illinois

Application December 20, 1948, Serial No. 66,191

7 Claims. (Cl. 223—96)

1

This invention relates to an improved garment hanger of the clamping type.

In a device of this type jaws are provided to engage the garment to be supported and the jaws in turn are supported by arms or other means which are hingedly connected to each other. Means are provided for urging the jaws into clamping engagement with each other, and separate spring means have generally been provided to urge the jaws apart when the clamping means is released. Thus, the insertion of a garment between the jaws is facilitated.

An object of this invention is to provide a garment hanger in which the parts are so shaped and arranged to avoid the use of a separate spring for urging the jaws apart.

In describing my invention, I have shown it as applied to a garment hanger of the type shown in Deknatel Patent No. 1,955,792 in which the hingedly connected arms are provided with crank portions. A clamping lever is pivotally mounted on one crank portion and engages the crank portion of the other arm to actuate the jaws. However, my invention is equally applicable to garment hangers employing other types of clamping means for urging the jaws into clamping engagement with each other and other types of hinged connection between the jaws.

Another object is to provide an improved garment hanger in which the resilience of the wire stock from which the arm and crank elements are made serves to hold the jaws in gripping engagement with each other when the clamping lever is operated, and which also serves to urge the jaws away from each other when the clamping lever is in its unoperated position.

The hinged connection between the elements is effected by providing one of the arm and crank elements with pintle portions and by providing the other of said elements with helical portions which surround the pintle portions. In other words, the latter element is wrapped around the pintle portions of the former to provide bearings.

I have found that the foregoing objects may be attained by shaping the parts in such a manner that one pintle and bearing is slightly out of alignment with the other. Assuming a position of the parts where the axis of each pintle portion is coincident with the axis of the bearing, the misalignment is such that the two axes intersect each other to form an angle. In other words, both axes are aligned with respect to one plane, but not with respect to a plane perpendicular to said common plane.

In such an arrangement there is one angular 55

position of the parts, called herein a neutral position, in which there is no stress on the parts. Where the pintles or bearings or both are resiliently mounted, as they are here since they are both formed from resilient wire stock, any angular displacement of the parts from the neutral position will cause a deformation of the pintles, or bearings, or both, which will tend to cause the parts to return to their neutral position, assuming that there is no play between the parts.

Actually, in the manufacture of a device of this type, there is likely to be a certain amount of play or clearance between the pintles and bearings which has the effect of permitting a certain amount of free movement of the parts in either direction from the neutral position, but the parts are so constructed that they will be stressed before the jaws are moved into their closed position.

20 However, the principles of this invention are applicable to garment hangers other than the specific type shown in the above-mentioned patent.

With reference now to the drawings in which 25 like reference numerals designate like parts:

Fig. 1 is a perspective view of a preferred embodiment of my invention with the jaws in an open position.

Fig. 2 is an enlarged sectional view taken along 30 line 2—2 of Fig. 3, and showing certain changed positions of the parts in dotted lines;

Fig. 3 is a sectional view taken along line 3—3 of Fig. 2;

Fig. 4 is a plan view of the parts shown in 35 Fig. 3;

Fig. 5 is a view similar to Fig. 3 but being taken along line 5—5 of Fig. 2, showing the parts in stressed position;

Fig. 6 is a plan view of the parts shown in Fig. 40 5; and

Fig. 7 is a view of a slightly modified construction; and Fig. 8 shows a further modification.

The garment hanger comprises a pair of jaws 10 and 11 which are preferably made of strips of wood which are lined with felt pads 12. The jaws are formed with openings which are adapted to receive the end portions of two rods 10a and 11a respectively which support the jaws. The rod 10a is provided with jaw arm portions 13 at either end which are separated by an intermediate portion comprising a crank 14 and crank arms 15. The rod 11a comprises jaw arm portions 16 which are separated by an intermediate portion comprising a crank 17 and crank 50 arms 18. The two portions between the crank

arms 18 and the jaw arm 16 are formed into helices 19 which embrace correspondingly disposed pintle portions 24 on the opposite rod. Thus, the jaws 10 and 11 are hingedly mounted with respect to each other.

The clamping lever 20 has a bent end 21 which pivotally engages crank 17. The clamping lever also has a camming portion 22 which is adapted to ride over crank 14 and bring the jaws into clamping engagement, this position of the parts being shown in Fig. 2, although the clamping lever is omitted for purposes of clarity. The crank 14 may be provided with roller bearing 23 which is preferably made of a strip of brass stock which is bent into more or less cylindrical shape as shown in Fig. 2. The bearing 23 serves to reduce frictional wear on the crank 14, but it may be eliminated insofar as the present invention is concerned.

The helices 19 and pintles 24 cooperate with each other to form two spaced hinged portions about which the jaws move. Each of the helices 19 are bent about 15° out of alignment with respect to the axis of rotation of the jaws about each other. Each of the pintle portions 24 are bent out of alignment in a like manner.

The bending is effected in such a manner that the axes of the two hinged portions form an included angle of about 150° when the jaws are in an open position. As indicated above, when the bent axes of the two pintle portions and of the two helices are aligned with each other, the parts are in what might be called in neutral position. The parts are bent in such a manner that this neutral position occurs when the jaws are in an open position, preferably about 90° to 135° apart. If there is no clearance between the pintle portions and the helices, any movement of the jaws toward each other from neutral position will stress the parts so that the jaws will tend to spring back to the neutral position.

In the manufacture of the particular garment hanger shown, the helices 19 are formed by wrapping the rod 11a around the pintle portions 24 of rod 10a. After the wrapping operation, the wire rod tends to spring back, resulting in a clearance between the helices and pintle portions.

Each cooperating helix 19 and pintle portion 24 constitutes a hinge portion. After the wrapping operation, the spaced hinge portions are bent out of alignment with each other while the jaws are maintained in an open position. This open position becomes the neutral position after the bending operation; and, therefore, the jaws are held, during the bending operation, in an angular position of between 90° and 135°.

The aforementioned clearance permits a certain amount of free movement of the parts before the hinge portions become stressed. For instance, in the embodiment shown, the clearance permits a free movement of about 40° on either side of the neutral position.

Figs. 3 and 4 show the parts in neutral position, the axis of each pintle portion coinciding with the axis of its corresponding helix. Here, the jaws are 110° apart, indicated by the upper dotted line position of the crank 14 in Fig. 2.

The neutral position selected is preferably that which will produce the maximum stressing of the parts when in closed jaw position. In this instance, where the clearance permits 40° free movement, the maximum stressing occurs at 70°, thereby suggesting the selection of 110° for the neutral position.

It is obvious, however, that the helices and

pintle portions may be bent when the jaws are in an angular position other than 110°. The foregoing angular measurements are given merely by way of example and as an illustration of the manner in which the maximum stressing action can be obtained. Entirely apart from the foregoing considerations, practically any angular position of the jaws can be selected as the neutral position just as long as the clearance is sufficiently small as to permit a certain amount of stressing as the jaws are moved into their closed position.

Figs. 5 and 6 show the position of the hinged portions when the jaws are closed, Fig. 5 being taken along line 5-5 of Fig. 2, and Fig. 6 being taken at right angles to the projection of Fig. 5. Here it will be seen that the helices and pintle portions have both been deformed, with the result that the axes of the pintle portions are more nearly in alignment with each other.

As shown in Fig. 7, the pintle portions 19 need not necessarily be straight portions. Due to the nature of the bending or drawing operations employed in the manufacture of the device, it is often difficult to get absolutely straight pintle portions. When the pintle portions are curved, the effective axis could be considered as being coincident with the axis of the helices when the parts are in that neutral position which provides the greatest amount of clearance.

It is not necessary that both helical portions be formed on one rod and both pintle portions on the other. For instance, in the modification shown in Fig. 8, the rod 10a is formed with one pintle portion 24a and one helical portion 19b, whereas the rod 11a is formed with one helical portion 19a and one pintle portion 24b. Furthermore, it is obvious that other types of hinged connection may be provided for the jaws 10 and 11, just as long as the construction is such that the two spaced hinged portions may be bent out of alignment with one another.

In operation, the hinge portions tend to hold the jaws apart when the clamping lever 20 is in the position shown in Fig. 1. When the clamping lever is swung upwardly into engagement with the roller bearing 23, after the jaws have been manually closed, continued movement of the clamping lever will draw the crank portions 14 and 17 together and will serve to lock the jaws in clamped position. This position of the cranks is shown in that dotted line position of Fig. 2 in which the crank 14 is disposed substantially vertically. The movement of the crank from the solid line position to the last-mentioned dotted line position is permitted by virtue of a stressing of the rods 10a and 11a in substantially the same manner as occurs in the device shown in the aforementioned patent.

The rods 10a and 11a may be formed from any suitable wire stock, such as a $\frac{1}{2}$ nd inch spring wire stock. For example, No. 9 bright basic steel wire has been found to be satisfactory.

As shown in Fig. 1, the outer end of the clamping lever 20 may be formed into a hook so that the garment hanger may be conveniently supported from a clothes rod. However, other supporting means may be provided, and the clamping lever may be utilized solely for clamping purposes.

The principles of my invention may also be applied to a garment hanger in which the hingedly connected jaws or other garment engaging elements are biased toward each other, or into

closed position, where such an arrangement is desired.

Although only a preferred embodiment of my invention has been described and shown herein, it will be obvious that various modifications and changes may be made in the construction shown without departing from the spirit of my invention as defined by the appended claims.

I claim:

1. In a garment hanger having two garment clamping jaws, separate means for supporting each of said jaws, said supporting means being provided with spaced hinge portions cooperating with each other to provide a hinged connection for said jaws, the axis of one of said spaced hinge portions being out of alignment with the axis of the other of said spaced hinge portions when said jaws are in an open position, and said hinge portions being resiliently mounted so that said supporting members are stressed when said jaws are in closed position whereby said jaws will tend to spring apart.

2. In a garment hanger having two garment clamping jaws, separate means for supporting each of said jaws, one of said supporting means including a pair of spaced bearings and the other one of said supporting means including a pair of spaced pintles, means for holding said jaws in clamping engagement with each other, said bearings and said pintles cooperating with each other to provide a hinged connection for said jaws comprising two spaced hinge portions, the axis of one of said spaced hinge portions being disposed at an angle to the axis of the other.

3. A garment hanger according to claim 2 in which said supporting means are formed from resilient wire stock.

4. In a garment hanger having two garment clamping jaws, separate means for supporting each of said jaws, one of said supporting means including a pair of spaced bearing elements and the other one of said supporting means including a pair of spaced pindle elements, means for holding said jaws in clamping engagement with each other, said bearing elements and said pindle elements cooperating with each other to provide a hinged connection for said jaws comprising two spaced hinge portions, the axis of one of said spaced hinge portions being disposed at an angle to the axis of the other, at least two of said elements being resiliently mounted.

5. A garment hanger comprising two jaws, a rod for supporting each of said jaws for pivoted movement with respect to each other, each of said rods comprising two end portions bent to form jaw arms and an intermediate portion including a crank, one of said rods having helical portions at points between said crank and said jaw arms and the other of said rods having pindle portions at points between said crank and said jaw arms, said helical portions surrounding said pindle portions to provide a hinged connection for said jaws, a clamping lever pivotally mounted on one of said cranks and adapted to engage the other of said cranks to bring said jaws into clamping engagement with each other, the effective axes of said helical portions being disposed at an angle to each other and the effective axes of said pindle portions being disposed at a similar angle to each other so that said jaws tend to spring apart from closed position.

6. A garment hanger comprising two jaws, a resilient rod for supporting each of said jaws

for pivoted movement with respect to each other, each of said rods comprising two end portions bent to form jaw arms and an intermediate portion including a crank, one of said rods having two spaced helical portions, one between said crank and each of said jaw arms, said helical portions being disposed at an angle to each other, and the other of said rods having two spaced pindle portions one between said crank and each of said jaw arms, each of said helical portions surrounding one of said pindle portions to provide a hinged connection between said rods, a clamping lever pivotally mounted on one of said cranks and adapted to engage the other of said cranks to bring said jaws into clamping engagement with each other, said pindle portions being disposed at an angle to each other, the plane of which angle is such that the effective axis of each pindle portion coincides with the axis of its cooperating helical portion when said jaws are open and disposed at an angle of not more than 135 degrees from each other whereby said rods will be stressed when said jaws are in closed position.

7. A garment hanger comprising two jaws, a resilient rod for supporting each of said jaws for pivoted movement with respect to each other, each of said rods comprising two end portions bent to form jaw arms and an intermediate portion including a crank, one of said rods having a helical portion disposed between said crank and one jaw arm and a pindle portion disposed between said crank and the other jaw arm, the axes of said portions being disposed at an angle to each other, and the other of said rods having a pindle portion disposed between said crank and one jaw arm and cooperating with said helical portion to form a hinged connection, and having a helical portion disposed between said crank and the other jaw arm and cooperating with the pindle portion of said first-mentioned rod to provide a hinged connection therewith, the axes of said helical and pindle portions of said second-mentioned rod being disposed at an angle to each other which is substantially equal to said first-mentioned angle so that in one position of the parts the effective axes of said pindle portions lie in a common plane and form an angle with each other and the effective axes of said helical portions lie in a common plane and form an angle with each other, means mounted on one of said cranks and adapted to engage the other of said cranks to bring said jaws into clamping engagement with each other, the angular relationship between the parts being such that the effective axis of each pindle portion substantially coincides with the axis of its cooperating helical portion when said jaws are open and disposed at an angle of not more than 135 degrees from each other whereby said rods will be stressed when said jaws are in closed position.
